POST-ADJUSTING MEANS FOR WIRE AND
NAIL DIRECTING APPARATUS

Marion F. Stephens, Sullivan, Ind.

Application January 22, 1945, Serial No. 573,954

4 Claims. (Cl. 248—161)

1

My invention relates to post-adjusting means designed primarily for directing apparatus particularly adapted for precision technique for intracapsular fracture of the hip but is not limited to such use.

In the extensive practice of hip-nailing there has been developed what is called the Smith-Peterson technique. It comprises the insertion of a guiding pin or wire in the shaft of the femur, the wire serving to guide a cannulated vitallium Smith-Peterson nail inserted in such a manner that it parallels and is in contact with the medial and anterior cortex of the neck of the femur. The guide, commonly called a Steinmann pin, is usually about three-thirty-seconds of an inch by ten inches and is removed from the bore of the nail after the latter has been properly positioned in the fractured neck of the femur. The Smith-Peterson nail for an adult is about five inches long and has a diameter of five-thirty-seconds of an inch although it is flanged and generally triangular in cross section. It extends through a hole drilled in the hard outer portion of the femur, the hole extending in line with the center of the acetabulum at approximately a 20° anterior angle. The nail extends through the neck and preferably into the head or ball-like portion of the hip joint, and its function is of course to re-enforce the head on the neck of the femur. For the best results, the nail must be nearly in the direct weight-bearing line of the joint and so positioned that it receives the support of the dense corticle bone on both sides of the distal fragment. The insertion of both the guide pin and the nail must be controlled at all stages by two-plane radiography and in the past the successful placement of such fixation devices has depended largely upon the senses of sight and touch of the surgeon and has required a high degree of skill.

A proposed apparatus for accurately placing the guide wire or pin, and hence the nail, in proper position in the fractured bone, comprehends a supporting and guiding means for the guide pin or wire, which means includes a post vertically and rotatably adjustable in a bearing, and it is the object of the present invention to provide a novel and advantageous means whereby an approximate adjustment of said post may first be made, and later when said approximate adjustment has been checked by radiography, to permit making a fine adjustment to accurately position the guide pin or wire.

In the accompanying drawings, Figure 1 is a side elevation.

2

Figs. 2, 3, 4 and 5 are detail horizontal sectional views on the correspondingly numbered lines of Fig. 1.

Figs. 6 and 7 are detail vertical sectional views on lines 6—6 and 7—7 of Fig. 4.

Fig. 8 is a detail rear elevation as indicated by line 8—8 of Fig. 1.

Fig. 9 is a fragmentary vertical sectional view on line 9—9 of Fig. 8.

Fig. 10 is a horizontal sectional view on line 10—10 of Fig. 1.

Fig. 11 is an enlarged detail horizontal section on line 11—11 of Fig. 8.

Fig. 12 is a fragmentary elevation of a portion of the side opposite that shown in Fig. 1.

Fig. 13 is an enlarged detail vertical section on line 13—13 of Fig. 4.

Fig. 14 is a fragmentary enlarged view similar to a portion of Fig. 4, partly in section.

20 In these figures in which like reference characters indicate corresponding parts, 20 denotes generally an upright support rising from a base 21 and carrying preferably at its top a transversely extending guiding or directing member 22 for 25 the pin, nail or other element which is to be supported and guided in its longitudinal sliding movement toward a predetermined point. The support 20 includes a vertical post 23, the lower portion of which is cylindrical and mounted for 30 slideable and rotatable movements in an upright tubular guide or bearing 24 which has its lower end fixed in the center of the base 21. The latter is preferably square as shown in Fig. 10 and adjacent its four corners are leveling feet 25 in the 35 form of screws threaded through the base or through nuts mounted therein. To assist in leveling the base, spirit levels 26 may be set in the base flush with its upper surface at points between its corners and center.

40 The base 21 is to be secured by suitable clamps (not shown) on the top of an operating table or the like after proper leveling and after proper positioning of the instrument with respect to the patient. The body of the patient is of course immobilized by the usual means associated with fracture and operating tables. When the table or other support on which the patient is held has not a sufficient top area to receive the base 21, it may be mounted on any suitable support which 45 will permit it to be properly positioned both lengthwise and laterally with respect to the patient's body.

The lower end of post 23 is supported on a follower plate 27 which is vertically adjustable in 50 the fixed guide tube 24 and to center the post,

its lower extremity enters an upstanding annular flange 28 formed on the follower and having an inwardly and downwardly beveled edge as shown in Fig. 1.

While any suitable means may be provided for adjusting and securing the follower in order to vertically adjust and secure the post, I preferably form on the edge of the follower a laterally projecting arm 29 from which rises a rack bar 30. These parts are in a laterally projecting and longitudinally extending extension 31 formed on tube 24 as shown in Figs. 1 and 2. Engageable with the rack through an opening in extension 31 is a pinion 31^a fixed to the inner end of a shaft 32, the outer end of which has a hand-wheel 33. Shaft 32 is journaled in a bearing 34 projecting from extension 31 as shown in Fig. 2.

The upper end of tubular guide 24 is formed with two spaced vertical slits 35 to provide a spring finger 36, the upper portion of which is within a collar 37 surrounding the upper portion of the tube 24. The collar has an upper inturned flange 38 to rest on the upper end of tube 24 and on its side is formed a lateral boss through which is threaded a clamping screw 39 adapted to engage the outer face of the spring finger 36. Within the upper portion of tube 24 and between it and the post 23 is a split bushing 40 substantially coextensive in length with the length or height of the collar as shown in Fig. 13, the longitudinal split in the bushing being spaced 90° from the axis of screw 39 as shown in Fig. 3. The bushing and the collar are held in their proper positions at the upper end of tube 24 by a bolt 41 which passes through these three parts. Bolt 41 has its head countersunk in the inner face of the bushing and a nut is threaded on its outer end. The bolt is located diametrically opposite screw 39 as shown in Fig. 3. It will be seen that on tightening the screw 39, the tube 24 will be frictionally locked to the bushing and the latter will be contracted around the post 23 so that the post will be clamped and secured against rotation in tube 24 and will also be held against upward sliding movement. When clamp screw 39 is loosened, post 23 may be rotated and it may be raised or lowered by turning hand-wheel 33.

By grasping and rotating post 23 an approximate adjustment of the pin guiding element 22 to an angular position in a horizontal direction may be made and that position then secured by tightening screw 39. It is desirable, however, to have a finer adjustment of element 22 in a horizontal direction, that is, about the vertical axis of post 23. To permit that being done, the cylindrical portion of the post is formed with a plurality of key-ways or grooves 42 which receive keys 43 formed in the bore of a collar 44 surrounding post 23, the collar being thus slidably but non-rotatably mounted on the latter. Projecting radially from collar 44 is an arm 45, the upper edge of which curves downwardly and merges into a flat segmental plate 46 formed at the outer end of the arm and having on its upper face a vernier scale 47. The latter coacts with a scale 48 divided into 360° and arranged on the upper face of a track or ring 49. This ring is concentric with the axis of post 23 and is supported by three radial arms or spokes 50 whose inner ends are secured at 51 to the top of collar 37. Rotatably mounted on post 23 and positioned between the hub 44 of the vernier arm and arms 51 supporting the graduated ring 49, is the hub 52 of an adjusting and clamping arm 53. The latter is radially disposed as shown in Fig. 4 and its outer end terminates

close to the inner edge of ring 49. Carried by the outer end of arm 53 is a vertically disposed clamping bolt 54, the flat head 55 of which is slidably engaged with the lower side of an annular flange 56 formed on the inner edge of ring 49. This bolt 54 passes freely through a clamping sleeve 57 and has a milled-edge nut 58 engaged with its threaded upper end, as shown in Fig. 6. Sleeve 57 has a transverse threaded opening to one side of its bore to receive a slow motion adjusting screw 59, one end of which is secured by a ball and socket joint to one side face of the arm 45 as shown in Figs. 4 and 14. The lower end of sleeve 57 frictionally engages the upper face of ring 49 and of arm 53 so that when nut 58 is screwed down on bolt 54, said parts will be clamped between the head of the bolt and the sleeve to frictionally lock arm 53 to ring 49. It will, therefore, be seen that when these parts are clamped together while screw 39 is loose, the rotation of slow motion screw 59 will cause arm 45 and hence post 23 to turn with respect to ring 49 and the vernier scale 47 will move with respect to the scale graduations 48, to thus obtain a fine angular adjustment of the pin guiding member 22 about the axis of post 23.

The angular adjustment in a vertical direction of the pin guiding member or element 22 is preferably obtained by the structure mounted on the upper part of post 23 and shown more particularly in Figs. 1, 8, 9, 11 and 12. The body portion of member 22 is preferably V-shaped in cross section as seen in Fig. 8 so that it is channeled or trough-shaped to support and guide the pin, the latter being indicated in dotted lines in Fig. 8. About midway of the body portion of member 22 is an integral depending shank or stem 60 having a transverse width equal to the width of the body and also having side faces which may be engaged by the arms of an inverted U-shaped spring clip 61. The central or connecting portion of this clip extends across the groove or trough in the body of member 22 to hold or retain the pin therein, particularly when X-ray pictures are being made. The clip is of course readily engageable with and disengageable from said guiding member. The lower end of shank 60 is reduced in thickness as shown at 62 and this reduced portion is formed with a recess 63 shaped to fit a squared central portion of a shaft 64. A screw, pin or the like 65 fastens these parts together.

Shaft 64 is mounted for oscillation at the top of post 23, the upper portion of which is square in cross section as seen in Fig. 5. The top of post 23 has a transverse recess to receive the reduced lower end 62 of the stem or shank, the recess forming spaced bearing ears 66. The latter have circular bearing openings to receive cylindrical portions 67 and 68 formed on shaft 64 beyond its squared central portion as shown in Fig. 11. At the outer side of the portion 67, the shaft is formed with another squared portion 69 which enters a square hole at the axis of a protractor 70. The graduations 71 on the latter coact with a vernier scale 72 arranged on a segmental plate 73 secured to a flat face of the squared upper portion of post 23, as shown in Figs. 8 and 12.

Mounted on the cylindrical bearing portion 68 of shaft 64 is a rotatably adjustable sleeve or hub 75 carrying a depending flat arm 76. A set screw 77 in a threaded boss on hub 75 is adapted to engage the portion 68 of shaft 64 to lock arm 76 for movement with the shaft. This clamping screw 77 permits of an approximate vertical angular adjustment of the pin guiding member 22

when the lower end of arm 76 is clamped between the points of two opposed adjusting screw 18 threaded through spaced projecting ears or lugs 19 formed at the ends of a transverse bar 80 fastened at its center in a recess in the flat face of post 23 as shown in Fig. 1. When a finer adjustment of member 22 in a vertical direction is desired, the slow motion screws 18 are adjusted to move the arm 76 and hence, shaft 64 and protector 70 relative to post 23. In this adjustment, the graduations 71 on the protector are shifted relative to the fixed vernier scale 72. The extremities of shaft 64 may be threaded to receive a threaded cap screw 81 at one end and a nut 82 at the other end to hold the parts assembled as shown in Fig. 11.

The cylindrical portion of post 23 is provided with graduations 33 which may be read in connection with the upper edge of hub or collar 44 so that the vertical adjustment of the pin guiding member 22 may be noted. The coacting scale graduations showing the horizontal and vertical angular adjustments of member 22 may also be noted so that such adjustments may be returned to at another time if necessary or desirable. When clamp screw 39 is loosened, the post 23 and all parts which it supports, may be removed from the guide tube 24 to permit such parts to be sterilized.

The use and advantages of the apparatus to correctly position the guide pin in a fracture of the neck of the femur will be readily understood from the foregoing by a surgeon familiar with hip-nailing and the Smith-Peterson technique. Its use may, however, be briefly stated as follows: After the patient is secured in the proper position on the table, the instrument is leveled, properly positioned and then clamped to the table in the proper position relative to the fractured joint. The pin is placed in the guiding member 22 and held in place by the clip. Member 22 is then adjusted vertically to the proper height by turning hand-wheel 33. Approximate adjustments of member 22 as previously described, are then made to give the pin the proper angular disposition both horizontally and vertically. X-ray pictures in both vertical and horizontal planes are made to check the position of the pin with respect to the fractured bone. The finer adjustments may then be made and further X-rays are taken to see that the pin is directed properly with respect to the fracture. After the incision has been made, the drill which cuts through the hard outer portion of the bone may be guided by the member 22. The pin while in member 22 is slid or pushed along its trough or channel and is gradually pushed through the soft inner portion of the bone, X-ray pictures being taken from time to time to see that the pin is properly directed. After the pin has been properly positioned, the hole is reamed to the proper size for the Smith-Peterson nail which telescopes the pin. The guiding member 22 may be used in guiding the reamer and the nail. When the nail is properly positioned, the pin is removed and the incision is closed.

The use of the apparatus will greatly shorten the time necessary for performing the operation and insure the accurate positioning of the pin and nail by a surgeon not particularly skilled in that class of operations. While the invention has been described as particularly well adapted to the nailing of hip joints, it will be understood that it may be put to other uses.

To those skilled in the art, changes in or modifi-

cation of the above described embodiment of my invention will be suggested and may be made without departing from the inventive concept thereof. Reference is, therefore, to be had to the appended claims to determine the scope of the present invention.

What is claimed is:

1. In an apparatus of the class described, a post, a bearing rotatably mounting said post, a track concentric with said bearing means fixedly securing said track to said bearing, one radial arm connected with said post for rotation with the latter, said one arm extending to said track, a second radial arm circumferentially spaced from said one arm and having a hub rotatably surrounding said post, means connecting the two aforesaid arms with each other and effective to cause said second arm to move with said one arm while said post is being turned in said bearing to an approximate desired position, and means for securing said second arm to said track after said post has been turned to said approximate position, said arm-connecting means including manually operable adjusting means for moving said one arm toward or from said second arm after the latter has been secured to said track, to obtain a fine angular adjustment of said post.

2. In an apparatus of the class described, a post, a bearing mounting said post for rotative and endwise adjustment, a track concentric with said bearing means fixedly securing said track to said bearing, one radial arm over said bearing and extending to said track, said one arm having a hub through which said post extends, said hub being slidably connected with said post to rotate with the same and to permit endwise adjustment of said post in said hub, a second arm circumferentially spaced from said one arm and having a hub through which said post extends slidably and rotatably, means connecting the two aforesaid arms with each other and effective to cause said second arm to move with said one arm while said post is being turned in said bearing to an approximate desired position, and means for securing said second arm to said track after said post has been turned to said approximate position, said arm-connecting means including manually operable adjusting means for moving said one arm toward or from said second arm after the latter has been secured to said track, to obtain a fine angular adjustment of said post.

3. In an apparatus of the class described, a post, a bearing rotatably mounting said post, a track concentric with said bearing means fixedly securing said track to said bearing, one radial arm connected with said post for rotation with the latter, said one arm extending to said track, a second radial arm circumferentially spaced from said one arm and having a hub rotatably surrounding said post, a manually operable clamp carried by said second arm and engageable with said track to secure said second arm to said track when desired, said clamp including a clamp member mounted on said second arm and turnable about an axis parallel with said post, an adjusting screw threaded through said clamp member at right angles to said axis, and means connecting said adjusting screw with said one arm, whereby prior to tightening said clamp, both of said arms may turn with said post when turning the latter in said bearing to an approximate desired position, and after tightening said clamp turning said adjusting screw will move said one arm with respect to said second arm, thereby

turning said post to obtain a fine angular adjustment of the latter.

4. In an apparatus of the class described, a post, a bearing rotatably mounting said post, a track concentric with said bearing means fixedly securing said track to said bearing, one radial arm connected with said post for rotation with the latter, said one arm extending to said track, a second radial arm circumferentially spaced from said one arm and having a hub rotatably surrounding said post, a bolt extending through said second arm near said track and disposed parallel with said post, the lower end of said bolt having a head underlying said track, a sleeve upon said bolt and resting on the upper side of said track, a nut on said bolt for moving said head and sleeve into clamping engagement with said track to lock said second arm to said bearing after said post has been turned to a desired

approximate adjustment, an adjusting screw threaded transversely through said sleeve at one side of said bolt, and means connecting said screw with said one arm, whereby said screw may be operated to move said one arm and obtain a fine adjustment of said post.
